UNITED STATES PATENT OFFICE

ROLAND B. BARBER, OF WHEELER ROAD, MARYLAND

SPRING COMPRESSOR FOR REMOVING POPPET VALVES

Application filed December 8, 1931. Serial No. 579,807.

My invention consists in new and useful improvements in a spring compressor and relates more particularly to that type of device which is adapted for inserting and removing the springs of poppet valves in internal combustion engines.

It is well known that with devices heretofore employed mechanics have experienced no end of difficulties in gaining access to the springs of poppet valves in order to compress the same preparatory to removing the valves for repairs and regrinding. Also considerable difficulty has been encountered in properly compressing the springs when assembling the valves and springs in an engine.

It is the object of my invention to overcome these difficulties and to this end I have provided a device which is extremely simple in construction and operation, as well as one which affords great ease of access to the parts of an engine. Another object of the present invention is to provide a spring compressor which is adjustable to accommodate various lengths and sizes of coil springs.

A still further and important object of my invention resides in my improved adjustable leverage mechanism for accomplishing the compression of valve springs.

With the above and other objects in view which will appear as the description proceeds, my invention consists in the novel features herein set forth, illustrated in the accompanying drawings and more particularly pointed out in the appended claims.

Referring to the drawings in which numerals of like character designate similar parts throughout the several views,

Fig. 1 is a perspective view of the spring compressor in released position.

Fig. 2 is a fragmentary detail showing the adjustable lever support or carriage.

Fig. 3 is a sectional view taken on line 3-3 of Fig. 2.

Fig. 4 is a plan view of a modified form of my invention showing an adjustable spring engaging yoke.

Fig. 5 is an enlarged detail showing the spring stop and retaining lip on the preferred form of spring engaging yoke.

Fig. 6 is a view in side elevation showing

the spring compressor in released position in full lines, and in compressed position in dotted lines, and

Fig. 7 is a top plan view of the compressor in released position.

In the drawings, 1 represents a main body portion, one end of which is provided with any suitable gripping means to serve as a handle (not shown), and the other end is provided with a bifurcated spring supporting yoke 2, the latter being either integral with the body portion 1 or secured thereto by any suitable means. The mouth 3 of the yoke 2 is transversely curved and preferably flares outwardly toward its open end so as to accommodate various sizes of springs.

4 represents a second bifurcated spring supporting yoke which is substantially the same in construction as the yoke 2, having a flaring mouth 5. The yoke 4 is free or disconnected from the body portion 1 and is preferably provided with a projection 6 at its rear end to serve as a handle or gripping element in applying the device as hereinafter set forth.

The yokes 2 and 4 are arranged in superposed relation and lie in substantially parallel planes, the yoke 4 being drilled at a plurality of points to receive cables or chains 7 and 8. In the form of my invention shown in the drawings, I have employed cables which extend through and are secured to the opposite wings of the yoke 4, the opposite ends of each cable extending downwardly and passing around rollers or pulleys 9 and 10 which are rotatably mounted on short shafts 9' and 10' respectively, which project transversely from the opposite outer sides of the wings of yoke 2. These pulleys may be secured in place by cotter pins or any other suitable means, and the wings of the yoke 2 are preferably recessed to accommodate the rollers as clearly shown in the drawings.

After passing over the rollers 9 and 10, the cables 7 and 8 are respectively secured to the free ends of arms 11 and 12 by any suitable means such as screws 13, rivets or welding. The opposite ends of the arms 11 and 12 are transversely drilled to accommodate a pivot shaft 14 whereby said arms are

pivots secured to the base 15 of a lever 16.

The inner end of the base portion 15 of the lever 16 is preferably bifurcated and provided with transverse apertures 17 whereby the lever 16 is pivotally mounted on the ful-

70
3 crum pins 18 of an adjustable carriage 19 hereinafter described in detail. As best shown in Fig. 2, said base member 15 is provided with a plurality of transverse apertures 20, any one of which is adapted to receive the arm supporting shaft 14, thus permitting the degree of leverage to be adjusted to suit conditions.

Referring to Figs. 2 and 3 it will be seen that the carriage or lever supporting member 19 is provided with a substantially semi-oval opening 21, the upper boundary of which is preferably transversely straight, said opening 21 being adapted to receive the main body portion 1 and to slide longitudinally thereon.

20
25 A portion of the surface of the body portion 1 adjacent the straight boundary of the opening 21 is preferably provided with a plurality of serrations or notches 23 which are adapted to be engaged by the straight edge 22 when the carriage 19 is in a tilted position as shown in Fig. 1. A spring 24 is mounted on the lower end of the carriage 19 with its free end adapted to engage the undersurface of the body portion 1 in such a position as to retain said carriage 19 in an angularly disposed or tilted relation with respect to the body portion 1, thereby normally causing the straight edge 22 to engage in the notches 23, locking said carriage against longitudinal movement in either direction on the body portion 1.

25
30 The underside of the carriage 19 is preferably provided with a tab 25 by means of which the operator may swing the carriage forwardly against the opposition of the spring 24 to release the carriage from locked position. It will be noted that the elongated aperture 21 in the carriage is of suitable dimension and shape to permit of this movement.

35
40 The spring retaining means in the yokes 2 and 4 may be of two different types. For example, as shown in Fig. 5 I may provide a series of stop pins 26 which extend vertically through the yokes, projecting above and below the horizontal surfaces thereof, said pins being adapted to engage behind the outer surfaces of the springs to act as rear stops. In addition to these rear stops I may provide a lip 27 on the undersurface of the yoke 4 and the upper surface of the yoke 2 to engage the side of the convolutions of the spring adjacent the respective yoke. Thus these two elements 26 and 27 tend to retain the spring in its proper relative position with respect to the yoke.

45
50 A modified form of spring retaining means is shown in Fig. 4 where, instead of the arrangement shown in Fig. 5, I provide an adjustable arc-shaped stop 28, which by means

From the foregoing it is believed that the advantages and operation of my improved spring compressor may be readily understood by those skilled in the art without further description, it being borne in mind that numerous changes may be made in the details of construction without departing from the spirit of the invention as set forth in the following claims.

10 What I claim and desire to secure by Letters Patent is:

1. A spring compressor comprising a body portion, a spring engaging member carried by said body portion, a second spring engaging member lying in a substantially parallel plane and in superposed relation to said first named member, a plurality of flexible connections secured at one end to said second member, their other ends being secured to 20 an eccentric lever mounted on said body portion, the intermediate portions of said connections passing over rollers secured to said first named member, and means for adjusting the longitudinal position of said lever 25 mounted on said body portion to take up any slack in said connections, whereby when a coil spring is interposed between said spring engaging members, the movement of said lever on its fulcrum will draw the second member toward the first to compress the 30 spring.

2. A spring compressor comprising a body portion, a spring engaging yoke carried by said body portion, a second spring engaging yoke lying in a substantially parallel plane and in superposed relation to said first named yoke, a plurality of flexible connections secured at one end to said second yoke, their other ends being secured to an eccentric lever 40 mounted on said body portion, the intermediate portions of said connections passing over rollers secured to said first named yoke, and means for adjusting the longitudinal position of said lever on said body portion 45 to take up any slack in said connections, whereby when a coil spring is interposed between said spring engaging yokes, the movement of said lever on its fulcrum will draw the second yoke toward the first to compress the 50 spring.

3. A spring compressor comprising a body portion, a spring engaging yoke carried by said body portion, a second spring engaging yoke lying in a plane substantially parallel 55 to said first named yoke, and arranged in a substantially vertical line therewith, a plurality of flexible connections secured to said second yoke and passing over respective guide means secured to said first yoke, and means on said body portion operatively engaging said connections, whereby tension 60 may be applied to said connections to draw said second yoke toward the first.

4. A spring compressor comprising a body portion, a spring engaging yoke carried by

said body portion, a second spring engaging yoke lying in a plane substantially parallel to said first named yoke and arranged in a substantially vertical line therewith, a plurality of cables secured to said second yoke 70 and passing over respective rollers secured to said first yoke, and means on said body portion operatively engaging said cables, whereby tension may be applied to said cables to draw said second yoke toward the 75 first.

5. A spring compressor comprising a body portion, a spring engaging yoke carried by said body portion, a second spring engaging yoke lying in a plane substantially parallel 80 to said first named yoke and arranged in a substantially vertical line therewith, a plurality of cables secured to said second yoke and passing over respective rollers secured to said first yoke, a carriage on said body portion, a lever pivotally secured to said carriage, means for connecting said cables to an eccentric point on said lever, and means for adjusting the longitudinal position of said carriage on said body portion. 85

6. A device as claimed in claim 5 including means for regulating the degree of leverage applied to said cables.

7. A device as claimed in claim 5 including means for locking said carriage in the 95 desired position on said body portion.

8. A device as claimed in claim 5 wherein said carriage consists of a member having a substantially elongated opening adapted to slidably engage said body portion, and spring 100 means for normally causing said member to assume a tilting position with respect to said body portion, whereby the vertical boundaries of said elongated opening are forced into gripping engagement with the adjacent 105 surfaces of the body portion.

9. A device as claimed in claim 5 wherein said carriage consists of a member having a substantially elongated opening adapted to slidably engage said body portion, spring 110 means for normally causing said member to assume a tilting position with respect to said body portion, whereby the vertical boundaries of said elongated opening are forced into gripping engagement with the adjacent 115 surfaces of the body portion, and a projection on said carriage to facilitate its release.

10. A spring compressor comprising a body portion, a bifurcated spring engaging yoke carried by said body portion, a second 120 bifurcated spring engaging yoke lying in a plane substantially parallel to said first named yoke and in substantially vertical alignment therewith, a plurality of cables secured to said second yoke and passing over respective anti-friction means secured to said first yoke, means carried by said body portion and operatively connected to said cables for applying tension to the latter to draw the second yoke toward the first, and means 125 130

on said yokes for retaining a coil spring in the proper relative position.

11. A device as claimed in claim 10 where-
in said last named means comprises stop
5 members for limiting the rearward move-
ment of said spring with respect to said yokes.

12. A device as claimed in claim 10 where-
in said last named means comprises stop mem-
bers for limiting the rearward movement of
10 said spring with respect to said yokes, and a
projecting lip for limiting the forward move-
ment of said spring.

13. A device as claimed in claim 10 where-
in said last named means consists of an ad-
15 justable stop member for limiting the rear-
ward movement of a spring with respect to
said yokes.

In testimony whereof I affix my signature.
ROLAND B. BARBER.
